US0D1005362S

(12) **United States Design Patent** (10) **Patent No.:** **US D1,005,362 S**
Holsten-Stuehmer et al. (45) **Date of Patent:** **** Nov. 21, 2023**

(54) **WEARABLE ROBOTIC EXOSKELETON WITH BELTS**

(71) Applicant: **FESTOOL GmbH**, Wendlingen am Neckar (DE)

(72) Inventors: **Esther Holsten-Stuehmer**, Hamburg (DE); **Björn Hipp**, Hamburg (DE); **Wladimir Lindt**, Esslingen am Neckar (DE); **Edwin Bunnik**, Maehringen Ulm (DE)

(73) Assignee: **FESTOOL GmbH**, Wendlingen am Neckar (DE)

(**) Term: **15 Years**

(21) Appl. No.: **29/826,537**

(22) Filed: **Feb. 14, 2022**

(30) **Foreign Application Priority Data**

Aug. 13, 2021 (WO) 107683

(57) **CLAIM**

The ornamental design for a wearable robotic exoskeleton with belts, as shown and described.

DESCRIPTION

FIG. 1 is a top back perspective view of a wearable robotic exoskeleton with belts showing our new design;

FIG. 2 is a front plan view thereof;

FIG. 3 is a back plan view thereof;

FIG. 4 is a top plan view thereof;

FIG. 5 is a bottom plan view thereof;

FIG. 6 is a left side plan view thereof; and,

FIG. 7 is a right side plan view thereof.

1 Claim, 6 Drawing Sheets
